(57) **CLAIM**

The ornamental design for a vacuum cleaner housing, as shown and described.

DESCRIPTION

FIG. 1 is a top, front, left side perspective view of a vacuum cleaner housing showing our new design;

FIG. 2 is a top plan view thereof;

FIG. 3 is a right side elevational view thereof, the left side being a mirror image thereof;

FIG. 4 is a front elevational view thereof;

FIG. 5 is a rear elevational view thereof; and,

FIG. 6 is a top, rear, right side perspective view thereof.

The broken lines showing structural elements in the drawings are included for the purpose of illustrating an environment of use and non-claimed subject matter, and form no part of the claimed design.
